(57) CLAIM

We claim the ornamental design for an adhesive bandage with decorated pad, as shown and described.

DESCRIPTION

FIG. 1 is a plan view of a first embodiment of an adhesive bandage with a decorated absorbent pad showing my new design;

FIG. 2 is a side elevational view thereof, the opposite side elevational view being a mirror image thereof;

FIG. 3 is an end elevational view thereof, the opposite end elevational view being a mirror image thereof;

FIG. 4 is a plan view of a second embodiment of an adhesive bandage with a decorated absorbent pad showing my new design;

FIG. 5 is a side elevational view of the embodiment of FIG. 4, the opposite side elevational view being a mirror image thereof;

FIG. 6 is an end elevational view of the embodiment of FIG. 4, the opposite end elevational view being a mirror image thereof;

FIG. 7 is a plan view of a third embodiment of an adhesive bandage with a decorated absorbent pad showing my new design;

FIG. 8 is a side elevational view of the embodiment of FIG. 7, the opposite side elevational view being a mirror image thereof;

FIG. 9 is an end elevational view of the embodiment of FIG. 7, the opposite end elevational view being a mirror image thereof;

FIG. 10 is a plan view of a fourth embodiment of an adhesive bandage with a decorated absorbent pad showing my new design;

FIG. 11 is a side elevational view of the embodiment of FIG. 10, the opposite side elevational view being a mirror image thereof;

FIG. 12 is an end elevational view of the embodiment of FIG. 10, the opposite end elevational view being a mirror image thereof;

FIG. 13 is a plan view of a fifth embodiment of an adhesive bandage with a decorated absorbent pad showing my new design;

FIG. 14 is a side elevational view of the embodiment of FIG. 13, the opposite side elevational view being a mirror image thereof; and,

FIG. 15 is an end elevational view of the embodiment of FIG. 13, the opposite end elevational view being a mirror image thereof.

The ornamental design which is claimed is shown in solid lines and stippling in the central portion of FIGS. 1, 4, 7, 10 and 13 of the drawings.

The dash dot dash broken lines depict portions of an adhesive bandage with decorated pad and form no part of the claim. The dark evenly dashed and spaced broken lines depict the claim boundary and form no part of the claim. The portions inside the claim boundary form a part of the claim. The lightly dotted portions of the decorated pad outside of the claim boundary form no part of the claim.
